ELECTRIC MOTOR STRUCTURE

Filed Aug. 12, 1930

UNITED STATES PATENT OFFICE

RALPH S. WHALEY, OF SEATTLE, WASHINGTON, ASSIGNOR TO PETROLEUM HEAT AND POWER COMPANY, OF NEW YORK, N. Y., A CORPORATION OF DELAWARE

ELECTRIC MOTOR STRUCTURE

Application filed August 12, 1930. Serial No. 474,718.

This invention is directed to an improvement in electric motor structures and relates particularly to certain structural details which are of advantage in oil burning apparatus and all of which will be brought out hereinafter.

One of the objects of my invention, however, is the provision of a construction whereby taking down and assembly of the apparatus in the field is facilitated, thereby making repairs and adjustments possible at the installation.

The drawing illustrates a sectional elevational view of an embodiment of my invention.

The apparatus to which this invention is directed is of the type employing a mechanically driven atomizing cup which I have designated 1.

20 2 designates the outer shell or snoot of the burner head which is permanently secured to the furnace front and projects inwardly into the combustion chamber of the furnace. This shell or snoot is of such a length as to permit of the use of standard firebrick about the same thereby not only eliminating the expense of special firebrick but insuring proper insulation of the burner from the combustion chamber.

25 30 3 designates the burner nozzle spaced from the shell or snoot 2 so as to provide an annular air channel 4 for the flow of air about the nozzle. The burner nozzle 3 and cup 1 are spaced from each other to provide a channel 5 surrounding the cup, this channel permitting of the flow of air from a fan 6 along the exterior of the cup to its tip.

Screwed upon the end of the nozzle 3 is a wide ring 3' which constitutes a continuation of the nozzle. This ring carries air deflectors 3" for imparting a whirling motion to the air passing along the channel 5 to the burner tip.

The atomizing cup 1 above referred to is 45 threaded upon a hollow shaft 16 which extends the entire length of the burner. The rotor of the fan 6 is also carried by this shaft, being keyed thereto as indicated at 6', the fan being held on the shaft by the cup 50 1 which clamps the fan to a shoulder 6"

provided for that purpose on the shaft. To remove the fan it is simply necessary to remove the atomizing cup, take off the front of the fan housing and slip the fan off the shaft. The shaft 16 also constitutes the armature shaft of an electric motor, the armature of which is designated 19 and the field structure 20. The field structure is held within the housing of the burner by set screws 18'. The armature 19 is mounted directly on the shaft 16 and held against turning with respect to the armature shaft 16 by a lock nut 21 threaded on the armature shaft, the nut forcing the armature against a shoulder 22 with which the shaft is provided. In order, therefore, to make repairs to the motor or to change the same, it is merely necessary to remove the end bell 17 of the burner housing by removing the bolts 18, loosen the two set screws 18', back off the nut 21, whereupon the armature and field coils may be slipped out of the housing.

This construction is also novel in another respect in that the portion 23 of the starting switch for the electric motor which is of the split phase type is carried by the nut 21.

Oil is supplied to the cup 1 through oil delivery pipe 24 which is threaded into a cap 25 bolted to the end plate 17 of the burner housing.

Intermediate the motor and the fan 6 I provide a worm 26 which is formed in a sleeve 27 mounted on the armature shaft 16 and a worm gear 28 cooperating with this worm, the gear 28 being carried by the shaft 29 for an oil pump by which oil is pumped to the pipe 24.

At each end of the sleeve 27 I provide the bearings 30 for the armature shaft. These bearings are lubricated by oil which is carried to the worm 26 from the oil case or housing in which the worm gear 28 is mounted and in order that the oil seeping to the bearings 30 may be filtered, packing 31 is provided adjacent each bearing and intermediate each bearing and the worm 26, this packing being held in place by a sheet metal sleeve 32 which surrounds the armature shaft and worm sleeve. This sleeve is held in place by a screw 36 carried by the casting 33 forming

a part of the burner housing. 34 designates a cap for the forward bearing 30, this cap being screwed upon the casting 33 of the housing. Consequently access may be had to this 5 bearing simply by removing the cup 1, the fan rotor, the cap 34 and the nut 34' which is screwed directly on the armature shaft 16. Access may be had to the rear bearing 30 after the motor has been removed by removing 10 cap 35 which is threaded upon the casting 33 of the nut 35' which is screwed upon the shaft 16.

From the foregoing, therefore, it will be appreciated that I have provided a motor 15 structure for oil burning apparatus wherein refractory of standard type, as distinguished from special refractory, may be employed about the burner snout.

It will be appreciated also that this insures 20 proper insulation of the burner from the combustion chamber.

It will be appreciated also that I have provided a construction which makes for easy 25 removal and assembly of the apparatus, it being a simple matter to remove almost any part of the apparatus in the field. As above 30 pointed out the atomizing cup 1 and the rotor of the fan 6 are easily removable from the shaft 16 simply, in the first instance, by unscrewing the cup 1 from the shaft and in the second instance by removing the forward part 35 of the fan housing whereupon the rotor of the fan may be slipped off the shaft. This is of advantage in this type of apparatus inasmuch as it provides for changing the capacity 40 of the burner at any time it may be desired. In this same connection it is to be noted that the ring 3' which carries the air deflecting members 3'' may readily be removed and replaced with a different type of deflector.

Attention has been called to the easy access 45 that may be had to the bearings 30 for the shaft 16. I might note at this point that these two bearings constitute the only bearings 50 for this shaft. As I have already indicated access may be had to the forward of these two bearings 30 by removing the atomizing cup, the fan rotor and then unscrewing the cap 34 and nut 34', while access may be had to the rear of the bearings 30 simply by 55 removing the cap 35 and nut 35' after the motor armature has been slipped off the shaft.

It is to be understood that changes may be 60 made in the details of construction above described within the purview of my invention.

What I claim is:—

An electric motor structure comprising in 65 combination an armature shaft, a shoulder on said shaft, an armature fitting said shaft, a nut on the shaft in contact with the armature for holding the same against said shoulder for rotation of the armature with the shaft, switching mechanism for the motor carried by said nut, a field structure, a housing for the 70 motor to which the field structure is remov-

ably attached and an end bell for the housing 75 removably secured to the housing.

This specification signed this 28th day of July, 1930.
